UNITED STATES PATENT OFFICE

100,712

DESIGN FOR A RADIANT HEATER

Luke O. Morin, Jr., Chattanooga, Tenn.

Application June 12, 1936, Serial No. 63,265

Term of patent 7 years

To all whom it may concern:

Be it known that I, Luke O. Morin, Jr., a citizen of the United States, residing at Chattanooga, in the county of Hamilton and State of Tennessee, have invented a new, original, and ornamental Design for a Radiant Heater, of which the following is a specification, reference being had to the accompanying drawing, forming part thereof.

The figure is a perspective view of a radiant heater showing my new design.

The heater is cylindrical in cross-section and the back portion not shown is substantially plain.

I claim:

The ornamental design for a radiant heater, as shown and described.

LUKE O. MORIN, JR.
